BUILDING CONSTRUCTION ELEMENT

Guy F. Kotrbaty, New York, N. Y.

Original application July 5, 1935, Serial No. 29,820, which in turn is a division of Serial No. 698,433, November 17, 1933. Divided and this application March 3, 1936, Serial No. 66,781. Renewed November 3, 1937

7 Claims. (Cl. 72—48)

This invention relates to building construction elements including side wall keying members and structural composite post and stanchion sections formed therewith.

5 This application is a division of my application Serial No. 29,820, filed July 5, 1935, for Composite construction members, which application is a division of my Patent No. 2,017,441 of October 15, 1935, the said patent being a continuation in part 10 of Patent 1,965,601 of July 10, 1934, which latter patent is, in its turn, a division of Patent No. 1,877,898 of September 20, 1932.

15 The specific details of my improvements having been set forth in the application above referred to, they will be presented here solely for the purpose of establishing the cooperative relationship between the several features, in order to more clearly illustrate the patentable novelty of the several parts in their specific structures and 20 in their combinations as previously set forth.

25 The examples shown are given merely by way of example, for since the underlying principles may be incorporated in other specific structures, it is not intended to limit the constructions to the forms shown, except as such limitations are clearly imposed by the appended claims.

In the drawing like numerals refer to similar parts through the several views of which

Figure 1 is a perspective of a side wall keying 30 member;

Fig. 2 is a plan view, partly in section, of abutted and joined walls, including the composite stud and key members herein; and

Fig. 3 is a vertical section taken on line 3—3 of 35 Fig. 2, the side wall keying members being shown in elevation.

40 Referring more specifically to the drawing there is shown in Fig. 1 a novel side wall keying member designated generally by the numeral 10. This member comprises a rail or head portion 11, usually of arcuate section and having edge portions 12 rounded and turned inwardly, as at 13, to form flange sections adapted to cooperate with auxiliary keyways of self-supporting building grid units in a manner to be described more 45 in detail hereinafter. The member 10 is provided with a central or web section having spaced walls 14 and terminating in angular bottom flanges 15 forming the base of the rail-shaped lateral keying member. The sections 15 are provided with edge beads 16 continued inwardly and generally parallel to the sections 15 to form bottom supports or flanges 17 having a central longitudinal aperture or gap therebetween. The key member 50 55 10 is preferably made of sheet metal of suitable gauge thickness, of the order of 17 to 26 wire gauge, depending on the stud or stanchion construction with which it is to be associated as a composite keying and structural supporting member. Due to the longitudinal slot 18 and the

spacing of the web parts 14 and the base flanges 17 a spring-gripping effect is given to the member and assures the perfect locking grip when slid or driven into keying position in angularly abutted building members as will be described in 5 further detail hereinafter.

The novel side wall keying member hereinabove described, is particularly adapted to be used

to secure angularly disposed wall members 20 to like members disposed at angles thereto and 10

usually forming part of a continuous wall construction. The self-supporting structural building units 20 may comprise spaced panel sections

21, spaced apart and secured by end-supporting

and keying members 22 having central key-re-

ceiving sections 23 adapted to receive spring-key-

ing members of suitable shape and configured to

the keyways, and designated generally by the

numeral 30. The end keyway sections 22 are pro-

vided at their ends with edge clipping sections 24 20

adapted to receive and secure panels 21 as by

crimping or to be secured to the same as by weld-

ing, brazing or soldering, as well as by mechani-

cal means such as bolts and nuts and rivets. The

edge clipping sections 24 form, with the central 25

web sections 25 of the end sections 22, recesses or

channels 26. Auxiliary keyways 27 are formed

by the juxtaposition of abutted inner channel

sections 26 of abutted and mutually interlocked

grid units 20. These channel sections and the 30

resultant keyway 27 formed thereby, serve to re-

ceive the head section 11 of the keying member

10, the beads or edges 12 of the rail section en-

gaging the inner side of the clip flange-securing

sections 24 and the body of the head 11 fitting 35

into the auxiliary keyway 27. The inner flange

sections or bottom of the head portions 13 of the

head section will serve as points of support for

the novel keying member and bearing surfaces

for the same. The base section of the keying 40

member 10 will fit into a suitably conformed key-

way or keying section 23, being engaged therein

in a spring-gripping relationship due to the ex-

pansion of the same along the line of the lon-

gitudinal slot 18 causing the base portions 17 to 45

approach each other. By suitably conforming

the parts to permit a driving grip into the key-

ways 23 the longitudinally arranged wall mem-

bers 20 may have like angularly arranged wall

members 20a secured thereto in permanent inter-

locked relationship without requiring special con-

structions to permit the same to be carried out in

an efficient manner.

The several wall sections or self-supporting

building units may be provided with insulating

fillers 40 of any suitable material. The usual

plastic surface finishes 50 may be applied to the

wall surfaces, although preformed surfacings may

also be used. In this connection the panelings

21 of self-supporting units may be formed of 60

finished materials which do not require plastic surfacings thereover.

The auxiliary keyways 27, and particularly those disposed on the exterior surface of a building wall are adapted to receive the heads of bolts 69 and secure fire-escapes, stagings, piazza members, and the like, to the stud or stanchion sections formed by the abutted keyways and keys. These several building members are designated generally by the numeral 61. They may be held in position in and on the buildings by nuts 62 cooperating with the bolts 60. The usual washers 63 may be also used. Where desired, the bolt head 69 may be ground flat on two sides to permit the passage of the members into the channels or keyways 27, after which the bolt may be rotated through a quarter turn to hold the same in position against the sections 26 causing them to be firmly seated when the nuts 62 are tightened in place.

It will be seen that by the provision of the auxiliary keyways 27, together with the improved side wall keying members 18, lateral or partition wall structures may readily be secured to main walls and building services, including fire-escapes, porch supports, and the like, may also be fixed in permanent relationship to the wall members and without requiring extra constructions or special equipment.

It will also be noted that due to the particular construction and arrangements of parts, including the novel keying members and associated keyways adapted to cooperate therewith, extra structural strength is built into and incorporated in building joints, whether in main walls or at points of juncture or joining of said walls to main walls. Thus, instead of the points of abutment of self-supporting building units forming points of weakness in a building structure, the incorporation of auxiliary side wall keying members in cooperation with other like members and/or with keying members and associated keyways of main wall sections, all being made of suitably conformed sheet metal stock, the maximum of structural strength and rigidity is secured and vertical structural members of composite constructions are simultaneously formed and made use of. The composite stud assemblies involve a maximum of structural strength with a minimum of metallic material and, at the same time, impose no drawbacks or difficulties in the way of architectural design features. In addition, standard keyways or building unit end sections of relatively light-gauge metal may be used, and variations in vertical strength of column sections may be taken care of by varying the gauge thickness of the sheet metal used in forming the auxiliary keying members 18, as well as that of the main keying members, here designated by the numeral 30.

It will now be appreciated that there has been provided novel structural building members, including spring-gripping auxiliary or side wall keying members of generally rail shape, adapted to fit in and engage suitably conformed keyways in the ends of self-supporting building units, as well as to engage the auxiliary keyways in the side of such building unit ends, whereby to permit the angular juxtaposition and locking of side wall building units to main wall units without requiring the interposition of special structural forms.

While certain novel features of the invention have been disclosed and are pointed out in the

annexed claims, it will be understood that various omissions, substitutions and changes may be made by those skilled in the art without departing from the spirit of the invention.

What I claim is:

1. A sheet metal lateral keying member comprising a head section and a generally flat foot section and an intermediate web section, the head section being of flattened arcuate configuration, the web section being formed of spaced, parallel portions terminating in edge flanges bent on themselves to form the foot portion of the member, the said head and foot sections being severally adapted to fit in and engage conformed keying sections in juxtaposed building unit members. 10

2. An angular wall joint construction, including linearly aligned building units having keying members therein and centrally thereof, together with auxiliary keyways formed at the edges of the abutted units, an angularly disposed unit 20 abutted against the juncture of the first said units, and expansible keying means having a double-walled, generally flat, flanged foot engaging the auxiliary keyway formed by the said first units and the separate keyway in the last-named 25 unit.

3. A sheet metal keying member for building units joined at right angles to a wall section comprising a generally rail-shaped structural member, the head, web and flanged foot being formed 30 of spaced sections, and the head being of generally semi-cylindrical cross-section.

4. A sheet metal keying member for building units joined at right angles to a wall section, comprising a generally rail-shaped structural 35 member, the head, web and flat flanged foot being formed of spaced walls; the head being of generally semi-cylindrical cross-section, and the flanges of the flat foot being divided by a continuous longitudinal slot. 40

5. A sheet metal keying member for building units comprising an elongated structure having spaced sides of unequal sides, one of said sides forming a semi-cylindrical, relatively narrow head portion, and the other said side forming a 45 substantially flat flanged foot section, both of said sides severally forming keyway-engaging sections, and an intermediate web section joining and integral with the sides, the said several sections having spaced walls.

6. A sheet metal keying member for building units comprising an elongated structure having spaced sides of unequal sides, one of said sides forming a semi-cylindrical, relatively narrow head portion, and the other said side forming a 55 substantially flat flanged foot section, both of said sides severally forming keyway-engaging sections, and an intermediate web section joining and integral with the sides, the said several sections having spaced walls, one of the side sections being externally slotted. 60

7. A sheet metal keying member for building units comprising an elongated structure having spaced sides of unequal sides, one of said sides forming a semi-cylindrical, relatively narrow 65 head portion, and the other said side forming a substantially flat flanged foot section, both of said sides severally forming keyway-engaging sections, and an intermediate web section joining and integral with the sides, the said several sections having spaced walls, and the member being expansible in all its parts. 70
